UNITED STATES PATENT OFFICE.

FRANK L. KINGSTON, OF CLEVELAND, OHIO, ASSIGNOR TO THE K.-D. CARBURETOR COMPANY, OF CLEVELAND, OHIO, A CORPORATION OF OHIO, (INCORPORATED JANUARY 18, 1917.)

PROCESS OF MAKING SHEET-METAL BALLS.

1,266,485.

Specification of Letters Patent. Patented May 14, 1918.

Application filed May 19, 1916. Serial No. 98,550.

To all whom it may concern:

Be it known that I, FRANK L. KINGSTON, a citizen of the United States, residing at Cleveland, in the county of Cuyahoga and 5 State of Ohio, have invented a certain new and useful Improvement in Processes of Making Sheet-Metal Balls, of which the following is a full, clear, and exact description, reference being had to the accompanying drawings.

This invention relates to a process for making hollow balls, and the balls made thereby, and has for its object to provide an improved method and article, a feature 15 of which is that the ball is made by cutting and pressing operations from a single piece of sheet metal.

Such balls are adapted for a variety of uses, one of which is to form a ball valve in a 20 carbureter, but the article may be used for other purposes, and the method is not limited to the exact manner of performing the same as herein shown and described.

The invention is illustrated in the accompanying drawings in which Figure 1 is a sectional view of cutting dies for cutting the blank. Fig. 2 is a perspective of the blank cut thereby. Fig. 3 is a sectional view of dies for cupping the blank. Fig. 30 4 is a perspective view of the cupped blank. Fig. 5 is a sectional view of the dies of a press for shaping the cupped blanks. Fig. 6 is a perspective view of the blank after it is acted on by the press shown in Fig. 5. Fig. 7 is a sectional view of a die press for 35 performing the final shaping operation, and Fig. 8 is a plan of the completed ball.

The figures illustrate the successive steps of the methods, and the condition of the 40 article after each step.

First, the blank shown in Fig. 2 is cut from a piece of sheet metal stock 6 by means of a male die 7 and a female die 8 fixed on a base or support 9. This blank is 45 star-shaped in general form, having a central body 10 and a plurality of segmental lobes or points 11. Six lobes are conveniently formed, but this number may be varied. Each edge 12 of each lobe describes 50 an arc which is substantially one-fourth the length of the circumference of the finished ball, or in other words, the body forms one

hemisphere of the ball and the lobes form the other. At the second step, the blank thus cut is placed in a centering device or 55 plate 13, over the circular opening 14 in a base plate 15, in which it is drawn to a cup by a plunger 16 having a hemispherical end, and this drawing operation shapes the body 10 into a hemisphere, and draws the lobes 60 up until the inner ends of their edges 12 are brought together, as shown in Fig. 4.

At the next step the lobes are pressed and bent inwardly toward each other, as shown in Fig. 6, by means of a die press consisting of 65 two members 17 and 18, the latter having a cavity in which the ball sets and the former having a shaping cavity with inclined and curved sides which draw the points or lobes together until the edges 12 are joined still 70 farther along the same.

At the final operation the article shown in Fig. 6 is acted on by a press to cause the edges 12 to approach closely together and give the final shape to the ball. This 75 press comprises two members 19 and 20 having hemispherical cavities the walls of which, when the members are brought together upon the article, force the points together and produce the completed article 80 shown in Fig. 8. For most uses, soldering is unnecessary and the edges 12 will unite firmly in consequence of the pressure, but they may be soldered to make a completely closed or watertight ball. The slight 85 opening 21, ordinarily left at the meeting point of the lobes, may be used for receiving or attaching a stem or pin if demanded by the subsequent use of the article, but for many uses it is immaterial whether this 90 opening is closed.

Having thus described my invention, what I claim is:—

The method of making a one-piece hollow ball, comprising forming a star shaped 95 blank with segmental lobes having arcuate edges each edge substantially equal in length to one quarter the circumference of the finished ball, cupping the body of the blank, and bending the lobes until their 100 edges meet.

In testimony whereof, I hereunto affix my signature.

FRANK L. KINGSTON.
